UNITED STATES PATENT OFFICE.

EDWARD J. D. KNAPP, OF CHICAGO, ILLINOIS, ASSIGNOR TO FRANK L. HUNTOON, OF ROBINSON, ILLINOIS.

DESIGN FOR A BED OR COUCH.

46,908.

Specification for Design.

Patented Feb. 2, 1915.

Application filed September 26, 1914. Serial No. 863,768. Term of patent 14 years.

To all whom it may concern:

Be it known that I, EDWARD J. D. KNAPP, a citizen of the United States, residing in the city of Chicago, in the county of Cook and State of Illinois, have invented a new, original, and ornamental Design for a Bed or Couch, of which the following is a specification, reference being had to the accompanying drawings, forming part thereof.

The figure shows the bed or couch in perspective as viewed diagonally from beyond the foot portion thereof.

I claim—

The ornamental design for a bed or couch substantially as shown.

EDWARD J. D. KNAPP.
